DEVICE FOR MAKING THE YARN LOOPS
OF CROCHETED RUGS

Marguerite G. Brooks, Darien, Conn.

Application May 1, 1950, Serial No. 159,227

2 Claims. (Cl. 66—1)

1

This invention relates to a device for use in making crocheted looped yardage of the type employed in making crocheted rugs, trimmings, fringes and other articles. Some material usually consists of an elongated row of yarn loops, joined to and held together by a crocheted backing or connecting strip formed by crocheting a strand of material separate from the yarn forming the loops. This is done by passing the strand forming the crocheted strip around successive loops of yarn as the crocheting operation proceeds. This requires inserting the crochet hook through or under each successive loop or a plurality of loops to draw the strand around it or them. Such an operation not only requires a complicated manipulation of the hook, but frequently results as well in considerable variation in the size of the different loops, when similarity in size is greatly desired.

An object of this invention is to provide a device for use in making crocheted looped yardage constructed and arranged to greatly simplify and expedite the operation.

A further object is to provide a device for this purpose arranged to insure the production of yardage having loops of substantially uniform size throughout.

A further object is to provide a device for this purpose so formed as to permit the crochet hook being quickly and easily inserted through successive yarn loops to crochet such loops onto the connecting or backing strip.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a perspective view on an enlarged scale showing the crocheting of looped yardage with a device constructed in accordance with one embodiment of this invention;

Fig. 2 is an end elevation of the device shown in Fig. 1, and

Fig. 3 is a side elevation thereof.

The illustrated embodiment of the invention comprises a member in the form of a substantially cylindrical block or plug 5 of wood, metal, plastic or other suitable material, so formed as to provide a loop-sizing exterior surface 6 shown in the drawing as cylindrical, around which the successive loops 7 of yarn are wound as the back-

ing or connecting strip 8 is crocheted by manipulation of the crochet hook 9 having the usual hooked end 11.

At each end the member 5 is formed with smoothly curved or beveled edges 12 over which the respective yarn loops 7 can freely slide without hindrance. One side of the member is so formed as to facilitate manipulation of the crochet hook in drawing the strand 13 being crocheted around successive free loops 14 to secure such loops to the backing or connecting strip 8. As illustrated, a groove 15 extends longitudinally along a part of the side of the member or block from one end thereof, so that the end 11 of the hook 9 can be freely and easily inserted through one or more free loops 14 by passing it along the groove 15 under one or more of these loops, as shown in Fig. 1.

The manner of using the device is illustrated in Fig. 1. As the loop-connecting strip 8 is progressively crocheted with the hook 9 successive stitches are made by drawing the strand 13 around one or more successive unsecured loops 14 of yarn which are successively wound around the plug or block 5 as the operation proceeds. This requires repeatedly thrusting the hook through such loops as above described. The groove 15 provides a space inside the loops through which the hook 9 can be thrust easily and quickly, as illustrated in Fig. 1, in order to accomplish this operation. This serves to incorporate successive uniform loops 14 with the connecting or backing strip 8 as the crocheting of the latter progresses. As the material is drawn along the block, the finished backing 8 and the connected loops 7 slide along the cylindrical ungrooved portion of the block and subsequently slip off the end. The cylindrical surface 6 provides a means for accurately sizing the successive loops so that the finished yardage is uniform throughout and greatly improved. The finished product is employed in making rugs, trimmings, fringes and other products. In making round rugs, for example, the looped yardage is wound in a spiral which is sewn together. Oval rugs are formed by winding the yardage in an oval form, or square rugs by winding it back and forth. The yarn loops form the nap of the rugs, while the crocheted strip forms the backing. If a looped nap is desired, the loops are not cut or clipped, but they may be clipped for a longer or shorter straight nap.

The specific details of the invention as illustrated can, of course, be variously modified and adapted within the scope of the appended claims.

Having thus set forth the nature of my invention, I claim:

1. A device for use in making yarn loops secured together by a crocheted strand forming a connecting strip, comprising a body member in the form of a short substantially cylindrical block at least one end of which is a substantially flat transverse surface and the side wall of the block forming a supporting surface for a series of loops of loop-forming yarn wrapped around it in successive loops of substantially uniform size, said body member being provided with a longitudinal open channel opening through said substantially flat end and extending therefrom to substantially the mid-length of the body to provide a passage through a free yarn loop passing around said body, and said channel being of a size to permit passage of a crochet hook longitudinally in the channel through the loop and beyond the end of the body to engage and draw a strand through the free loop and secure said loop to the crocheted connecting strip.

2. A device for use in making yarn loops secured together by a crocheted strand forming a connecting strip, comprising a body member in the form of an elongated block having side walls forming a loop supporting surface for a series of loops of loop-forming yarn wrapped around the body in successive loops of substantially uniform size and which are slidable along the body to pass

off one end, the opposite end being a transverse substantially flat surface, said body provided with an open sided groove opening through said latter end and extending from said end longitudinally to about the mid-length of the body to provide a space within a free yarn loop passing around said body, and said groove being of a size to permit passage of a crochet hook longitudinally in the groove through the yarn loop and beyond the end wall to engage and draw a strand through said yarn loop and secure it to the crocheted connecting strip.

MARGUERITE G. BROOKS.
